FOLDED SHEET

Samuel Shapiro, New York, N. Y.

Application September 18, 1940, Serial No. 357,203

5 Claims. (Cl. 206—57)

My invention relates to the folding of sheets of material such as paper and the like, used for napkins, doilies, towels, or similar articles.

The main object of my invention is to so fold an originally large blank or sheet of material as to reduce same to relatively small compass so that it can be packaged and handled advantageously.

Another object of my invention is to so fold the original sheet or blank of material that it presents a number of points at which it can be handled for quick and easy unfolding.

Another object of my invention is to fold a blank having an odd number of coextensive sections in such manner as to result in a fold of four thicknesses.

A further object of my invention is to so fold an originally large sheet or blank of material that the portions or panels into which the sheet is subdivided are arranged in symmetrical and balanced relation and form a finished folded article having a uniform number of thicknesses throughout.

Other objects of my invention will in part be obvious and in part be pointed out hereinafter. My invention will be described in relation to its use as a napkin although it is not to be limited to that use only.

In the drawing annexed hereto and forming a part hereof—

Fig. 1 is a plan view of a sheet or blank before being folded, the component sections of the sheet and the lines of fold being indicated by dot and dash lines;

Fig. 2 is a perspective view of the sheet or blank of Fig. 1 after the first two lateral folds have been completed, the lines and directions of the third and fourth lateral folds being indicated;

Fig. 3 is a perspective view showing four lateral folds completed;

Fig. 4 is a perspective view of the sheet in its final folded condition with the four lateral folds and one transverse fold completed in accordance with one form of the invention;

Fig. 5 is a perspective view of a modified fold, also in accordance with my invention in which is shown the blank of Fig. 1 with the first two lateral folds completed, as in Fig. 2, but with the direction of third and fourth lateral folds indicated as being made in the direction opposite to that shown in Fig. 2;

Fig. 6 is a perspective view of this modification of my invention showing four lateral folds completed;

Fig. 7 is a perspective view of the modified fold

of Fig. 6 in its final position with the four lateral folds and one transverse fold completed;

Fig. 8 is a perspective view of the fold of Fig. 3 with two transverse folds in accordance with another modification of my invention; and

Fig. 9 is a perspective view of the fold of Fig. 6 with two transverse folds in accordance with another modification of my invention.

The sheet or blank I use is preferably of paper or other easily foldable material. As shown in Fig. 1, sheet 10 is of rectangular shape and comprises seven coextensive portions or sections. Of these, there are two large main sections 14, one smaller section 16, and four other and smaller sections 18. Each of sections 18 is one-third the width of sections 14 and one-half the width of section 16. Two of these sections 18 are located along the lateral edges of sheet 10, and the remaining sections are located therebetween.

In producing the fold of my invention in accordance with the form of Figs. 1, 2, 3, 4 and 8, I fold sheet 10 lengthwise along lateral line 20—20 to bring panels 18a, 14a and 18a into overlapping relation to part of the sheet, and I fold the opposite side of sheet 10 lengthwise along lateral line 22—22 into overlapping relation to the remainder of sheet 10 by bringing the outer edges 15 and 17 together. Thus, as seen in Fig. 2, section 18a overlies half of section 16, section 14a and 18b overlap sections 14b and 18c respectively, and section 18d overlies the other half of section 16. With the first two folds completed, the area of sheet 10 has been halved.

I further reduce the blank by folding same lengthwise along lateral fold lines 24—24 and 26—26 (as indicated in Fig. 2), and bringing the newly formed edges 21 and 23 together. The outer edges 15 and 17 of blank 10 are close together on the outside of the fold and are easily available for grasping so that the blank may be easily and quickly expanded for use.

Considering the blank as reduced to the ultimate form shown in Figs. 3 and 4, same has four layers of equal width. The top, or outermost layer, consists of three of the smallest sections 18a, 18d and 18b of equal width, disposed in side-by-side relationship. The second layer consists of medium sized section 16 and smaller section 18d. The next layer consists of one large section 14b and the bottom layer consists of one large section 14a.

This top layer, composed of the three narrower sections 18a, 18d, 18b, has closed or "rolled" outer longitudinal edges along the fold lines 24—24, 26—26. On the top thereof it has two open or

raw edges 15, 17, and two closed or "rolled" edges 21, 23.

The fold of Figs. 3 and 4 may be further reduced in size. For instance, as in Fig. 4, the blank of Fig. 3 is folded transversely along the medial line 28-28, forming eight layers, and in Fig. 8, two transverse folds are made along lines 30-30 and 32-32, dividing the blank into three parts, forming twelve layers.

In the modified form of Figs. 5, 6, 7 and 9, parts similar to those of the form of Figs. 1 to 4, will be given similar reference indicia. Starting with the same blank 10 and the same number, arrangement and size of sections 14, 16, 18, and folding the blank along the longitudinal lines of folds 20-20, 22-22, I fold the blank to the form shown in Fig. 5, wherein sections 18d, 18a, 14a and 18b overlie respectively sections 16, 14b and 18c. In the form of my invention illustrated in Figs. 1 to 4, I folded the blank, after the completion of the first two folds, in such manner that the layer composed of the three smaller sections 18a, 18d and 18b appeared on the outside of the napkin. In this modification, however, I fold the blank laterally along the fold lines 24-24 and 26-26 so that sections 16 and 18c are on the outside and the layer made up of the three smaller sections is on the inside, the result being shown in Fig. 6.

Thereafter, one transverse fold may be made along line 28-28, or two transverse folds along lines 30-30, 32-32, may be made, as it is desired to further reduce the blank (see Figs. 7 and 9 respectively).

In all modifications of my invention, my fold has four lateral layers. Two of these layers consist of one large section each. A third layer in each case consists of one medium-sized and one small section, and the fourth layer in each case consists of three small equal-sized sections. The layers are all equal in width and thickness and the fold is balanced and symmetrical.

With the three section layer on the outside, the peripheral lateral edges 15 and 17 may be utilized for unfolding the napkin for use. With the three section layer on the inside of the fold, a smooth surface is presented which is neat, and permits easy stacking of large numbers of napkins. In all forms of my invention, all lateral edges are closed or "rolled," forestalling any possibility of raw edges interfering in any way with the handling or dispensing of the napkins.

In all modifications of my invention, every

layer is of the same length and width, and the fold is of uniform thickness throughout. The forward edge portion of each napkin can thus be flexed easily and uniformly and napkins may be used by removing same from a stack or bundle in dispensing machines such as disclosed in my prior Patent No. 1,965,060, dated July 3, 1934.

Having now described my invention, what I claim and desire to secure by Letters Patent is:

1. A rectangular paper sheet having an odd number of coextensive parts folded upon itself on lines parallel to the side edges thereof into four layers of equal width, in which one of the layers comprises but one of the parts, a second layer comprises another of the parts, a third layer comprises two of the parts, and the fourth layer comprises three of the parts, the longitudinal margins of the folded sheet being closed.

2. A rectangular paper sheet having seven coextensive sections of equal length, four of which sections are of equal width, two of which sections are each three times as wide as each of the four sections, and a seventh section which is twice as wide as each of the four, the article being folded into four layers of equal width, one of which comprises one wide section, a second of which comprises the second wide section, the third of which comprises one narrow and the seventh section, and the fourth of which comprises three of the narrower sections, the longitudinal margins of the folded sheet being closed.

3. A rectangular paper sheet as in claim 2, in which the fourth layer, composed of the three narrower sections, comprises an outermost layer of the folded sheet.

4. A rectangular paper sheet as in claim 2, in which the fourth layer, composed of the three narrower sections, comprises an inner layer of the folded sheet.

5. A rectangular paper sheet having an odd number of coextensive parts folded upon itself on lines parallel to the longitudinal edges thereof into four layers of equal width, the longitudinal margins of the folded sheet being closed, one of the layers comprising but one of the parts, a second layer comprising another of the parts, a third layer comprising two of the parts and the fourth layer comprising three of the parts, said fourth layer having thereon and between the outer longitudinal margins two open edges and two closed edges.

SAMUEL SHAPIRO.
